No. 37,477.

Patented June 27, 1905.

UNITED STATES PATENT OFFICE.

EDWARD FERGUSON CHANCE, OF SMETHWICK, NEAR BIRMINGHAM, ENGLAND, ASSIGNOR TO CHANCE BROTHERS AND CO. LIMITED, OF SMETHWICK, NEAR BIRMINGHAM, ENGLAND.

DESIGN FOR PLATE-GLASS.

SPECIFICATION forming part of Design No. 37,477, dated June 27, 1905.

Application filed March 25, 1905. Serial No. 262,104. Term of patent 14 years.

To all whom it may concern:

Be it known that I, EDWARD FERGUSON CHANCE, a subject of the King of Great Britain, residing at Glass Works, Smethwick, 5 near Birmingham, England, have invented a new, original, and ornamental Design for Plate-Glass, of which the following is a specification, reference being had to the accompanying drawing, forming part hereof.

10 The drawing represents a face view of a

piece of plate-glass ornamented with my design.

I claim—

The ornamental design for plate-glass as shown.

EDWARD FERGUSON CHANCE.
